UNITED STATES PATENT OFFICE.

KENNETH L. CHILDS, OF DETROIT, MICHIGAN.

AUTOMOBILE BODY CONSTRUCTION.

Application filed November 17, 1922. Serial No. 601,480.

To all whom it may concern:

Be it known that I, KENNETH L. CHILDS, a citizen of the United States, residing at Hotel Stevenson, 46 Davenport, Detroit, in the county of Wayne and State of Michigan, have invented certain new and useful Improvements in Automobile Body Construction, of which the following is a specification.

10 This invention relates to automobile or carriage construction and has for its object an improved body material for this purpose.

Heretofore it has been customary to construct the body of automobiles from aluminum and sheet steel. The aluminum is relatively expensive and easily bent and marred after painting. Sheet steel bodies are open to numerous objections such as relatively 15 heaviness and liability to bend and mar when painted. Furthermore, the sheet steel bodies easily rust under the paint and cause a great deal of trouble in preserving the finish.

20 The invention relates more particularly to a body construction including a skeleton frame and an exterior wall secured thereto.

According to a feature of the invention, the exterior wall, which is secured to the 25 skeleton frame, comprises a slightly flexible and yieldable foundation with a layer of flexible finishing fabric over the foundation, the term "finishing fabric" being herein used as defining any yieldable pliable material 30 such as cloth or leather capable of being stretched over the foundation and provided with an exterior finishing surface.

A further feature of the invention includes the use of a non-rigid or pliable material to afford a smooth support for the 35 flexible finishing fabric.

The use of a skeleton frame with a slightly flexible and yieldable foundation such for instance as a strong wire mesh produces a 40 strong body without the objectionable rigidity of prior constructions, the body being more elastic and flexible than an all metal body and yet having sufficient rigidity to withstand shocks or jars without undue dis- 45 torsion or buckling. Also the wall of a body constructed in this manner is sound deadening and heat insulating and the entire body is practically noiseless being substantially free from rumble, vibration, or 50 rattle.

The non-rigid or pliable material not only

affords a smooth support for the flexible finishing fabric but since it has some degree of elasticity it tends to expand outwardly when the fabric is stretched tightly over it and maintains the fabric in smooth condition.

In the drawings:

Fig. 1 is a side elevation of an automobile closed body with parts broken away showing the new construction.

Fig. 2 is a section taken through a portion of the back of the body.

Fig. 3 is an enlarged detail showing the body material.

The present invention permits the construction of the body below the belt moulding as well as above, of a material which is yieldable, flexible and which has a great durability of finish.

I employ preferably a wooden frame construction, although it is possible of course to use a metal frame. To the wooden frame is secured, by staples or otherwise, a heavy wire mesh *a* which in a large measure takes the place of the metal panels used in the ordinary body construction. The wire is preferably a 19 gauge wire and the mesh is preferably two to the square inch. Metal panels not only provide a cover and finish but also brace the frame construction and bear part of the strain. Hence this foundation wire forms a fair, and a lighter equivalent, of metal in connecting together the frame members and giving the whole a rigid construction. Furthermore, the foundation wire serves as a relatively strong yet slightly flexible and yieldable support for the layers of material laid thereover.

The first layer of material superimposed on the wire mesh foundation is a layer of cotton wadding *b*; over this is laid a hard and strong fabric material, such as buckram. Three layers of buckram are, preferably, laid over the wadding. These are designated *c* in the drawings; over the buckram is laid a high grade finishing cloth designated *d*. I find the most suitable material for this purpose is a material known on the market as Meritas leather cloth. This is unusually well adapted for the purpose I have in view. In a general way I will describe the desirable characteristics of the finishing fabric. It should be a high grade fabric impregnated with a material such as varnish, or some of the pyroxylin compound. Meritas leather cloth is preferable to cloth im-

2
pregnated with pyroxylin compounds as this takes varnish to much better advantage. This makes the material water-proof, and at the same time forms a high glossy finish for the outside very similar to the so-called patent leather only much more flexible and durable. This gives a high polish to the car, and has a much greater durability than the ordinary highly polished painted surface.

10 It will be evident that the body material above explained has many characteristics superior to the ordinary metal body panel. In the first place it does not mar nor dent 15 under the ordinary stresses but both the superimposed layers and the foundation material have a capacity for flexing and distorting within appropriate limits which prevent the blow from permanently marring, scratching or injuring the body. The 20 finish may be easily renewed and inexpensively, by varnishing at long periods. In case the finish is injured it may be readily removed by simply taking out a section of 25 the superimposed layers or a complete section of the composite material. All that is necessary to effect this, is to take off the moulding and disengage the material from its fastenings.

30 What I claim is:

1. In an automobile body construction the combination of a frame forming the skeleton of the body and an exterior wall construction comprising a slightly flexible and yieldable foundation material connecting the skeleton frame members to brace the same and give shape to the exterior wall construction and a finishing fabric supported over the foundation material.

40 2. In an automobile construction the combination of a frame forming the skeleton of the body and an exterior wall construction comprising a slightly flexible and yieldable wire mesh foundation, connecting the skeleton frame members to brace the same and give shape to the exterior wall construction and a finishing fabric supported over the foundation material.

45 3. In an automobile body construction the combination of a frame forming the skeleton of the body and an exterior wall construction comprising a slightly flexible and yieldable foundation material connecting the skeleton frame members to brace the same and give shape to the exterior wall construction a finishing fabric supported over the foundation material and a layer of yieldable material between the foundation material and the finishing fabric.

50 4. In an automobile body construction, the combination of a frame forming the skeleton of the body, and an exterior wall construction comprising a relatively strong foundation material, a yielding material

laid over the foundation material, and a fabric finishing material overlaying the yielding material.

5. In an automobile body construction, the combination of a frame forming the skeleton of the body, and an exterior wall construction comprising a relatively strong foundation material, a soft and yieldable wadding overlaying the foundation material, a strong fabric overlying the wadding, and a finishing material bearing a highly polished water-proof exterior surface.

6. In an automobile body construction, the combination of a frame forming the skeleton of the body, and an exterior wall construction made up of a composite material including a foundation material of a relatively strong and heavy reinforcing substance, a wadding of soft material laid over such foundation, a strong fabric, such as buckram laid over the wadding, and a finishing fabric, comprising a material having a relatively highly polished water-proof exterior surface.

7. In an automobile body construction, the combination of a frame forming the skeleton of the body, and an exterior wall construction comprising a strong wire mesh foundation, a wadding laid over the mesh, buckram laid over the wadding, and a finishing material having a highly polished, water-proof exterior surface.

8. In an automobile body construction, the combination of a frame forming the skeleton of the body and an exterior wall construction including a relatively heavy wire small mesh connecting the skeleton frame members to brace the same and give shape to the exterior wall construction, a wadding or packing material supported over the wire mesh and a finishing fabric supported over the wadding.

9. In an automobile body construction, the combination of a frame forming the skeleton of the body and an exterior wall construction including a foundation of relatively heavy wire small mesh connecting the frame members and bracing the same and serving to shape the exterior wall construction, a packing or wadding material laid over the foundation material and a finishing material laid over the wadding and having a water-proof exterior finish.

10. In an automobile body, the combination of a skeleton frame, and a wall construction below the belt line comprising a slightly flexible and yieldable foundation of foraminous material applied to the skeleton frame and capable of bracing and connecting the members of the skeleton frame and giving contour to the body, and a fabric provided with a finished exterior surface and suitably supported over the foundation material.

11. In an automobile body, the combina-

tion of a skeleton frame and a wall construction below the belt line comprising a relatively light but stiff foundation material applied to the skeleton frame and capable 5 of bracing and connecting the members of the skeleton frame and giving contour to the body, a soft, yieldable packing material laid over the foundation material, and a fabric provided with an exterior finishing 10 surface, supported over the packing material.

12. In an automobile body, the combination 15 of a skeleton frame and a wall construction below the belt line, comprising a relatively light but stiff foundation material applied to the skeleton frame and capable 20 of bracing and connecting the members of the skeleton frame and giving contour to the body, a soft yieldable packing material spread over the foundation material, a strong textile material stretched over the packing and a fabric provided with an exterior 25 finishing surface stretched over the textile material.

13. In an automobile body, the combina-

tion of a skeleton frame and an exterior wall construction located below the belt line, comprising a relatively strong wire mesh connecting the members of the skeleton frame and bracing the same and giving contour to the body, a packing material spread over the wire mesh, and a yieldable, pliable material spread over the packing material and provided with an exterior finishing surface. 30

14. In an automobile body, the combination 35 of a skeleton frame and an exterior wall construction located below the belt line, comprising a relatively strong wire mesh connecting the members of the skeleton 40 frame, bracing the same and giving contour to the body, a packing material spread over the wire mesh, a strong textile fabric drawn over the packing material, and a yieldable, pliable finishing material having an exterior 45 finishing surface drawn over the textile material.

In testimony whereof I affix my signature.

KENNETH L. CHILDS.
